CLAIM

The ornamental design for linked dispenser assemblies, as shown and described.

DESCRIPTION

FIG. 1 is a top, front, left perspective view of two linked dispenser assemblies of different widths showing the new design.

FIG. 2 is a top view of the two linked dispenser assemblies of different widths showing the new design.

FIG. 3 is a bottom view of the two linked dispenser assemblies of different widths showing the new design.

FIG. 4 is a left view of the two linked dispenser assemblies of different widths showing the new design.

FIG. 5 is a right view of the two linked dispenser assemblies of different widths showing the new design.

FIG. 6 is a front view of the two linked dispenser assemblies of different widths showing the new design.

FIG. 7 is a rear view of the two linked dispenser assemblies of different widths showing the new design.

FIG. 8 is a top, front, left perspective view of an alternate embodiment with two linked dispenser assemblies of narrow widths showing the new design.

(Continued)

FIG. 9 is a top, front, left perspective view of an alternate embodiment with two linked dispenser assemblies of wider widths showing the new design.

FIG. 10 is a top, front, left perspective view of an alternate embodiment with three linked dispenser assemblies of two different widths showing the new design.

FIG. 11 is a top, front, left perspective view of an alternate embodiment with four linked dispenser assemblies of two different widths showing the new design; and,

FIG. 12 is a top, front, left perspective view of an alternate embodiment with five linked dispenser assemblies of two different widths showing the new design.

The left and right sides of the article for the implementations seen in FIGS. 8-12 are identical to that shown in FIGS. 4 and 5. The broken lines in the drawings depict portions of the linked dispenser assemblies that form no part of the claimed design.
